United States Patent Office

Des. 188,193
Patented June 14, 1960

188,193

GUN

Eugene M. Stoner, 5830 W. 74th St., Los Angeles, Calif.

Filed July 23, 1958, Ser. No. 51,900

Term of patent 14 years

(Cl. D30—1)

Fig. 1 is a top plan view of a gun showing my new design;

Fig. 2 is a side elevational view;

Fig. 3 is a front end elevational view;

Fig. 4 is a side elevational view opposite to the side shown in Fig. 2.

Fig. 5 is a bottom plan view; and

Fig. 6 is a rear end elevational view.

I claim:

The ornamental design for a gun, as shown.
